UNITED STATES PATENT OFFICE.

STERLING W. DAWSON, OF CHICAGO, ILLINOIS.

GOLF CLUB.

Application filed June 1, 1926. Serial No. 112,779.

My invention relates to golf clubs and more particularly to putters.

The principal object of the invention is to provide a putter which will facilitate the employment of a manner of gripping, of which I believe I am the originator and which I have found very effective when properly used.

Another object of the invention is to provide a putter which, in a measure, will insure that the golfer uses the club in the proper manner.

A further object of the invention is to provide a putter with an improved striking head which is admirably suited for a club embodying the other features of improvement to which this invention relates.

In the accompanying drawings wherein I have illustrated a preferred embodiment of my invention, Figure 1 is an elevational view of my improved putter. Figure 2 is an elevational view of the upper end of the putter shaft and its sleeve, this view illustrating how the handle portion of the shaft is intended to be grasped by the left hand of a right-handed player. Figure 3 is an elevational view of the shaft and sleeve, showing the latter in one of its lowered positions. Figure 3^A is a section taken on the line 3^A-3^A of Figure 3. Figure 4 is a view, partly in section and partly in elevation, of the putter shaft and its sleeve, looking directly toward one of the sleeve apertures. Figure 5 is a top plan view of the club head, the shaft and its socket appearing in section. Figure 6 is a front elevational view of the club head. Figure 7 is a transverse sectional view of the club head taken on the line 7-7 of Figure 5, and Figure 8 is a sectional view illustrating a modified arrangement whereby to provide the desired pin and slot connection between the putter shaft and its sleeve.

Similar characters of reference refer to similar parts throughout the several views.

The putter shown in the drawings comprises a striking head 10, and a shaft 11, which is received in a shaft socket 12, which is, or may be, formed integral with the head. The head, which is preferably but not necessarily formed of cast aluminum, preferably comprises a vertical striking face 13, and a flat horizontal upper surface 14. The striking face 13 preferably has no loft whatsoever, but in practice may be rough-

ened in any suitable manner, as by providing it with ridges and grooves, indentations, or the like. The rear surface of the head, indicated at 15, is preferably a plane surface which is parallel to the striking face 13. The sole, or under surface, of the striking head is preferably straight from side to side, as is clearly illustrated in Figure 6, but is preferably curved convexly from front to rear, as is illustrated in Figure 7, to minimize the likelihood of a shot being spoiled by reason of the engagement of either the front or rear lower edges of the head with a worm cast or other small object which may be encountered upon a green. The shaft socket 12 is preferably so disposed that the shaft 11, is at an angle of substantially 18 degrees from the vertical when the club head is presented to a ball with its upper surface 14 parallel to the surface of the green. I prefer to provide the upper surface 14 of the club head with a pair of lines 16 and 17, the line 16 being parallel to the plane of the striking face 13, and the line 17 being at right angles to the plane of such striking face. When the club head is formed of uncoated aluminum, the lines 16 and 17 are conveniently provided by forming small grooves in the surface 14, which are filled with dark enamel or other suitable material which will retain its position and make the said lines distinct.

While I have ascertained from experience that best results can be secured when the striking head is constructed substantially as herein described, I do not limit myself to a striking head of this character as the other features of my club, which I shall now describe, may be employed in putters having striking heads quite different from the one herein shown and described.

The shaft 11 is conveniently but not necessarily formed of wood and is provided at its upper end or handle portion with a longitudinal slot 18 which extends downwardly several inches from the upper end of the shaft. At a point somewhat below the lower end of the slot 18 the cross section of the handle portion of the shaft is considerably reduced by providing it with diametrically opposite depressions or cut-outs which provide the elongated flat spots 19 and 20. The flat spot 19 is preferably although not necessarily somewhat longer

than the flat spot 20, and has its upper end terminating somewhat above the corresponding end of the flat spot 20.

5 Mounted upon the handle portion of the putter shaft, for limited reciprocating movement thereon, is a sleeve 21 which is preferably in the form of a tube of aluminum, or any other suitable metal, but may be formed of a variety of materials, such as 10 fibre, hard rubber, or the like. The sleeve is provided with a pin or key 22 which rides in the shaft slot 18 to permit relative longitudinal movement between the sleeve and shaft, the said pin or key, however, effectively preventing relative rotary movement 15 between the sleeve and the shaft.

If desired, the sleeve may be keyed to the shaft by striking inwardly projecting portions 22^a from the metal of the sleeve for 20 engagement in the slot 18, as is illustrated in Figure 8.

The club shaft is preferably provided at 25 its upper end with a cap or ferrule 23, which is held in position by any suitable means not shown. It will thus be observed that upward movement of the sleeve upon the shaft is limited by engagement of the sleeve with the cap or ferrule 23, while downward movement of the sleeve upon the shaft is 30 limited by engagement of the key with the lower end of the shaft slot 18.

The sleeve is provided with a pair of apertures 24 and 25, the aperture 24 being located opposite and being adapted to expose 35 the shaft's flat spot 19, the aperture 25 being located opposite and being adapted to expose the shaft's flat spot 20. The aperture 24 is preferably somewhat longer than the aperture 25, and has its upper end located 40 somewhat above the upper end of the aperture 25, because, as will be more fully hereinafter explained, the aperture 24 is intended to receive both the thumb and forefinger of the hand of a player, while the 45 aperture 25 is merely intended to receive the second finger.

The sleeve 21 is preferably somewhat loose 50 upon the shaft, that is to say, it is preferably sufficiently loose so that it is necessary for the player to grasp the club properly, as hereinafter explained, in order to retain 55 the sleeve at any desired adjusted position upon the shaft.

Earlier in this specification I alluded to 55 a manner of gripping, of which I believe I am the originator, the proper use of which the club of the present invention is intended to facilitate. Briefly stated, this manner of gripping the club is as follows:

60 The player (assuming that he is a right-handed player) grasps the shaft of the club between the forefinger and the second finger of his left hand, with the thumb and the third and fourth fingers of such hand resting 65 upon the handle portion of the shaft.

The hand should be so disposed that the shaft is substantially parallel with the medial longitudinal line of the wrist. This disposition of the left hand of the player upon the club is illustrated in the drawing. 70 The manner of applying the right hand to the club is not particularly important so far as this specification is concerned. Suffice it to say that the right hand is placed upon the shaft below and adjacent to the left hand in a manner which seems natural to the player.

I have found that when the shaft of a putter is gripped by a player in the manner just mentioned, excellent results can be secured, as is attested by the fact that some of the leading professional and amateur golfers have adopted this manner of gripping in their putting. One of the principal advantages of this style of gripping is the 80 fact that it eliminates, or tends to eliminate, pronation of the left hand. There are other reasons why this manner of gripping is desirable and effective, but since this invention is concerned with club construction, and not 85 with the technique of the game, I shall not bother to mention them in this specification.

I have found that the type of putter shown in the accompanying drawings is 90 greatly superior to the types of putters now in common use, when the new and improved manner of gripping herein briefly mentioned 95 is employed. In the first place, the handle portion of the ordinary putter is too thick to be comfortably grasped between the first 100 two fingers of the hand, as is illustrated in Figure 2. Furthermore, it is desirable that the handle portion of the club be firmly grasped between the first two fingers of the hand. This cannot be easily or comfortably 105 done when the surfaces engaged by such fingers are curved surfaces. By providing the shaft of my improved club with the depressed, flat spots 19 and 20, I am enabled 110 to reduce the cross section of the shaft and at the same time increase the area of contact between the shaft and the fingers between which the shaft is grasped.

The flat spots 19 and 20 are elongated and 115 the sleeve 21 is movable relative to the shaft because it is desirable that the left hand of the player grasp the shaft at different points along its length in making putts of different length. Ordinarily, the player will 120 grasp the shaft substantially as illustrated in Figure 2 when making a long putt and will place his same hand an inch or more lower when making a very short putt. It will be understood that the sleeve may be moved up or down to expose various portions of the flat spots 19 and 20, as determined by the length of putt about to be 125 made.

The fact that the sleeve 21 is quite freely 130 movable upon the club shaft requires that

the player grasp both the flat spots 19 and 20 and the outer surface of the sleeve quite tightly in making a shot. As there is some tendency among players not to grasp the club firmly with the thumb and all of the fingers of the left hand, it will be understood that the presence of the loose sleeve tends to overcome this fault.

As is illustrated in the drawings, the longer of the sleeve notches 24 is adapted to expose the flat spot 19 for engagement by both the thumb and forefinger of the player's hand, whereas the shorter of these apertures 25 exposes the flat spot 20 for engagement by the second finger of the player's hand.

Having thus illustrated and described a preferred embodiment of my invention, what I claim as new and desirable to secure by Letters Patent of the United States is:

1. A golf putter comprising a shaft, a reciprocating sleeve on the handle part of said shaft, and an elongated flat spot on said handle part, there being an opening in said sleeve through which different portions of said flat spot may be exposed and touched by a finger of a hand grasping said sleeve.

2. A golf putter comprising a shaft, a reciprocating sleeve on the handle part of said shaft, a pin and slot connection between said sleeve and handle part preventing relative rotary movement while permitting relative longitudinal movement between said sleeve and handle part, an elongated flat spot on said handle part, and an aperture in said sleeve adapted to expose different portions of said flat spot.

3. A golf putter comprising a shaft, a sleeve reciprocably mounted on the handle part of said shaft, said handle part having a portion thereof which is reduced in cross section by forming oppositely located elongated flat spots on said handle part, said sleeve being provided with oppositely located apertures adapted to expose different portions of said flat spots.

4. A golf putter comprising a shaft which has a handle part of reduced cross section, a sleeve reciprocably mounted upon said shaft, and apertures in said sleeve adapted to expose different portions of that part of the handle part which is reduced in cross section as aforesaid.

5. A golf putter comprising a shaft, a sleeve mounted on the handle part of said shaft, means permitting relative longitudinal movement between said sleeve and handle part and preventing relative rotary movement between the same, said handle part being reduced in cross section by forming oppositely located longitudinal flat spots thereon and apertures formed in said sleeve to expose said flat spots and to accommodate the fingers of a player.

6. A golf putter provided with oppositely located flat spots on its handle part and a sleeve reciprocably mounted on said handle part provided with apertures through which various portions of said flat spots may be exposed.

7. A golf club comprising a shaft, a sleeve reciprocably mounted on said shaft, there being an aperture in the sleeve through which the shaft may be engaged by a finger of the hand grasping said sleeve.

8. A golf club comprising a shaft, a sleeve reciprocably mounted on said shaft, means permitting relative longitudinal movement between the shaft and sleeve and preventing relative rotary movement between the same, there being an aperture in said sleeve through which the shaft may be engaged by a finger of the hand grasping said sleeve.

9. A golf club comprising a shaft, a sleeve reciprocably mounted on said shaft and a pair of oppositely located apertures in said sleeve through which the shaft may be engaged by fingers of a hand grasping said sleeve.

In witness whereof, I hereunto subscribe my name this 29th day of May, 1926.

STERLING DAWSON.
